TUNING INDICATOR TUBE

Herbert M. Wagner, Newark, N. J., assignor, by
mesne assignments, to Radio Corporation of
America, New York, N. Y., a corporation of
Delaware

Application September 29, 1937, Serial No. 166,251

6 Claims. (Cl. 250—27.5)

My invention relates to electron discharge devices, more particularly to such devices useful as visual indicators of voltage and having a fluorescent electrode which is rendered luminous and has the appearance of a pattern of light, which changes in response to the change in the magnitude of the applied voltage, a device of this character being particularly useful as a tuning indicator in radio receiving sets. The present invention is an improvement over a device of the general character described and claimed in my Patent No. 2,051,189, issued August 18, 1936.

The tuning indicator described in the patent referred to above comprises an envelope having within it a straight thermionic equipotential cathode provided with two separate emitting sections, one of which is surrounded by amplifier elements which may comprise a control grid and anode, and the other of which is surrounded by the tuning indicator elements of the tube consisting of a straight control electrode parallel to the cathode and a dish-shaped anode coated on its inside surface with fluorescent material, the anode being concentric with and surrounding the cathode and the control electrode. In operation electrons flow from the cathode to the fluorescent anode or target with sufficient velocity to bombard the fluorescent anode and render it luminous. The control electrode is connected to the amplifier anode and the tube so connected into a receiving circuit that when the circuit is tuned to resonance with an incoming signal the luminous portion of the plate is of a predetermined width, preferably the device is so connected that the luminous portion of the anode of the tuning indicator section of the tube is of maximum width, the dark portion of minimum width, when the circuit is tuned to resonance, and preferably the entire anode is made fluorescent and the dark portion disappears.

In some cases with the usual voltages applied to the anode and with space charge limitation of the current between cathode and anode, the life of the fluorescent coating is made comparatively short because of the large current the fluorescent anode receives. In addition the increased current to the fluorescent anode causes undue heating and undesirable results. Because of these factors the voltages which can be applied to the fluorescent anode are limited.

It is the principal object of my invention to provide an electron discharge device of the type described, particularly suitable for use as a tuning indicator, in which the life of the fluorescent coating is increased and in which the heating ef-

fects caused by the fluorescent anode current are minimized, and in which the range of voltages which can be applied to the fluorescent anode is extended.

The novel features which I believe to be characteristic of my invention are set forth with particularity in the appended claims, but the invention itself will best be understood by reference to the following description taken in connection with the accompanying drawing in which Figure 1 shows an electron discharge device embodying my invention with parts broken away to show details of construction; Figures 2 and 3 are top views with parts removed to show the tuning indicator portion of the tube and the pattern of light under different voltage conditions; Figure 4 is an enlarged perspective view of the electrode construction of the tuning indicator section of a tube shown in Figure 1; Figure 5 is a perspective with parts broken away of a modification of the electrode construction of the tuning indicator section of the tube, and Figure 6 is a partial transverse section taken along the line 6—6 of Figure 5; and Figure 7 is a circuit diagram embodying a tuning indicator tube made in accordance with my invention.

The electron discharge device or tuning indicator tube shown in Figure 1 comprises an evacuated envelope 10 provided with the usual stem and press 11 and base 12. Supported from the press are a cathode 13, preferably the conventional indirectly heated equipotential type, and a grid 14 concentric and preferably coextensive with and surrounding the cathode, and an anode 15 surrounding the grid. While shown as a triode this section of the tuning indicator tube could be of any other multi-element type.

The tuning indicator elements of the tube are placed at the upper end of the mount. The cathode 13 is extended upwardly and provided with a second emitting section 16 adjacent which is placed the control electrode 17 which may be a rod or a vane shaped from sheet material and placed edgewise to the cathode. This control electrode 17 is supported from and connected at 40 to one of the side rods of the anode 15. Surrounding and concentric with the emitting portion 16 of the cathode is an anode 19 shaped like a dishpan having a collar 20 and a coating 21 fluorescent under electron bombardment. The electrons emitted from the cathode and striking the anode with sufficient velocity, cause it to fluoresce. A cap 22 is positioned over the top end of the cathode 13 to confine the electrons to the emitting portion, the collar 20 preventing elec-

trons from reaching the glass walls of the envelope over the top of the anode. The cap 22 is supported from the dishpan-shaped anode and preferable electrically connected thereto by means 5 of side rods 23 positioned 90° from the control electrode as best shown in Figure 4. The cap 22 also serves as an electrostatic shield to prevent any stray charges that might develop on the glass envelope from affecting the electron stream from 10 the cathode to the fluorescent anode.

In this type of tuning indicator the electrons travel radially outward from the cathode to the fluorescent coating on the anode in a wide beam. The extent of the surface of the anode reached 15 by the electron beam is determined by the voltage on the control electrode 17. The less negative this electrode is with respect to the anode 20, that is the more positive with respect to the cathode 16, the greater the area of the anode covered 20 by the beam and the greater the area of the fluorescent portion of the anode. The control electrode 17 is at a positive potential with respect to the cathode. The advantages of this are that the boundaries of the electron beam are sharp 25 and well defined, there can be a high concentration of electrons at the edges of the luminous areas of the anode so that the edges are brighter and stand out more prominently, a high current to the luminescent anode and hence high luminosity is obtained with low anode voltages, and 30 the control electrode can be coupled directly to an amplifier. The tube is not critical to variations in cathode temperature, and it can also be used with either alternating or direct voltages 35 and currents.

The tube is viewed from the end so that the pattern of light is viewed as shown in Figures 2 and 3. As shown in Figure 2 when the control electrode is at a potential near that of the cathode 40 the anode fluoresces only over the area indicated by the shaded lines. As the electrode becomes more positive more of the surface of the anode fluoresces until at a predetermined voltage the entire surface of the anode 20 fluoresces. 45 This is the pattern which is shown in Figure 3 and which is obtained when the circuit in which the tube is used is tuned to resonance. Under these conditions the edges of the luminescent portion of the fluorescent anode just touch so 50 that the dark space is at its minimum or just disappears.

In accordance with my invention I position 55 around the cathode 16 a helically wound grid 16a, which is close to and connected at its ends to the cathode sleeve. In a tube made in accordance with my invention I used for this purpose a wire having a diameter of 0.010 inch wound fifty turns to the inch. The helix diameter is only a few thousandths of an inch larger than 60 that of the coated cathode. I found that in a tube made in accordance with my invention the moving fluorescent edges of the beam were sharp and distinct. Using a grid in the manner described will decrease the fluorescent anode current so that both the life of the coating and the heating effects described above are substantially 65 eliminated, and will permit the extension of the anode voltages which can be applied to the fluorescent anode.

70 In a modification of my invention shown in Figures 5 and 6 I provide the grid 16a with a pair of side rods 16b upon which the grid is wound. The grid is secured to the cathode by having opposite ends of the two side rods welded to the 75 cathode. In order to compensate for the elec-

tron shadow which these side rods would cast on the fluorescent coating I provide the top cap 22 with the wide ribbon support members 23a positioned opposite and close to the grid side rods. These support members being at a positive potential with respect to the side rods counteract the influence of the negative potential of these side rods so that the shadow which would normally be caused by these side rods is practically eliminated on the target or fluorescent 10 anode. A control electrode 24a is provided.

In Figure 7 I show a circuit embodying a tube made in accordance with my invention. The anode 15 of the triode section and the anode 19 of the tuning indicator section are electrically 15 connected to each other through a resistor 25. The fluorescent anode is connected directly to a source of voltage supply 26. When no current flows from cathode 13 there is no voltage drop in resistor 25 and the anode 15 and control electrode 17, which is connected to it, are at substantially the same potential as the anode 19 of the tuning indicator section of the tube. Under these conditions the pattern of light forms a complete annulus as shown in Figure 3, and the 25 anode fluoresces around its entire inner sloping surface. When a current flows in the circuit of the anode 15 a potential drop develops across the resistor 25 so that the anode 15 and control electrode 17 are made more negative with respect 30 to the anode of the tuning indicator section of the tube 20, and approaches the potential of the cathode, producing a pattern of light such as indicated in Figure 2. The magnitude of the current through the triode portion of the tube is 35 determined by the bias on the control grid 14.

In the circuit shown, a diode detector or rectifier 27 has its anode 28 and its cathode 29 connected to opposite sides of the secondary of the intermediate or radio frequency transformer 32 40 tuned by condenser 36, the cathode being connected through the resistor 30 and by-pass condenser 31. The cathode side of the transformer 32 is connected to the control grid 14 through resistor 33, the grid being by-passed by means 45 of by-pass condenser 34 so that a bias is impressed on the grid 14. The conductor 35 may be connected to the automatic volume control circuit. In the arrangement shown with the set untuned and no signal passing through the 50 transformer 32, no current passes through resistor 30 and no bias is developed. The grid 14 is at ground potential and permits current to flow through the triode section of the tube under which conditions the control electrode 17 is at 55 a potential near that of the cathode as described above, the light pattern takes the form shown in Figure 2. With the set tuned to a signal a rectified current passes through resistor 30 developing a drop across this resistor and impressing a bias on the control grid 14 of the triode through the resistor 33. This reduces the current passing through the triode in proportion to the bias impressed upon the grid so that the control electrode 17 becomes more positive with 60 respect to the cathode 13. The constants of the various elements are so chosen that when tuned to resonance the pattern of light is of the greatest width or forms a completely annular form 65 such as shown in Figure 3.

70 While I have indicated the preferred embodiments of my invention of which I am now aware and have also indicated only one specific application for which my invention may be employed, it will be apparent that my invention is by no 75

means limited to the exact forms illustrated or the use indicated, but that many variations may be made in the particular structure used and the purpose for which it is employed without departing from the scope of my invention as set forth in the appended claims.

What I claim as new is:

1. An electron discharge device having an envelope, a cathode within said envelope for emitting electrons, an anode surrounding said cathode and having its interior surface coated with a fluorescent material for receiving electrons from said cathode to produce a luminous annular shaped pattern on said anode, a control electrode positioned between said anode and said cathode for determining the area of fluorescent surface of the anode reached by the electrons from said cathode and a grid surrounding said cathode between said cathode and control electrode and adapted to be maintained at a potential not greater than that of the cathode.
2. An electron discharge device having an envelope, a cathode within said envelope for emitting electrons, a dish-shaped anode surrounding said cathode and having its interior surface coated with a fluorescent material for receiving electrons from said cathode to produce a pattern of light, a straight rod-like control electrode between said cathode and said anode and parallel to the cathode, and a grid surrounding said cathode between said cathode and control electrode and electrically connected to said cathode.
3. An electron discharge device having an envelope, a cathode within said envelope for emitting electrons, a dish-shaped anode surrounding said cathode and provided with a fluorescent coating for receiving electrons from said cathode, a cup-shaped member positioned over the end of said cathode and electrically connected to said dish-shaped anode for confining the electrons from the cathode to the surface of the anode, and a control electrode comprising a straight rod-like member parallel to the cathode for determining that portion of the surface of the anode reached by electrons from the cathode to cause the anode to fluoresce, and a grid surrounding said cathode between said cathode and control electrode and electrically connected to said cathode.
4. An electron discharge device having an envelope, a straight thermionic cathode within said envelope having two separate emitting sections thereon, a grid and anode surrounding one of said
5. An electron discharge device having an envelope, a cathode within said envelope for emitting electrons, an anode surrounding said cathode and having its interior surface coated with a fluorescent material for receiving electrons from said cathode to produce a luminous annular shaped pattern on said anode, a control electrode positioned between said anode and said cathode and parallel to said cathode, and a grid having oppositely disposed side rods surrounding and closely spaced from said cathode, said side rods being connected to said cathode, and a cup-shaped member positioned over the end of the cathode and having support members electrically connecting said cup-shaped member to said anode for confining the electrons from the cathode to the surface of the anode, said support members being parallel to and closely adjacent to the grid side rods for eliminating the shadow effects of said side rods during operation of the electron discharge device.
6. An electron discharge device having an envelope, a cathode within said envelope for emitting electrons, an anode surrounding said cathode and having its interior surface coated with a fluorescent material for receiving electrons from said cathode to produce a luminous annular shaped pattern on said anode, a control electrode positioned between said anode and said cathode and parallel to said cathode, and a grid having oppositely disposed side rods surrounding and closely spaced from said cathode, said side rods being connected to said cathode, and a cup-shaped member positioned over the end of the cathode, and ribbon-like support members electrically connecting said cup-shaped member to said anode and positioned parallel to and closely adjacent the side rods of said grid for eliminating the shadow effects of said side rods during operation of the tube.

HERBERT M. WAGNER.
